UNITED STATES PATENT OFFICE.

FRANKLIN ELIJAH SMITH, OF WEYMOUTH, ENGLAND, ASSIGNOR TO VICKERS
LIMITED, OF WESTMINSTER, ENGLAND.

AUTOMOBILE TORPEDO.

1,147,275.

Specification of Letters Patent. Patented July 20, 1915.

Application filed March 7, 1914. Serial No. 823,072.

To all whom it may concern:

Be it known that I, FRANKLIN ELIJAH SMITH, a subject of the King of Great Britain, residing at Portland Harbour Works, 5 Weymouth, county of Dorset, England, have invented certain new and useful Improvements in Automobile Torpedoes, of which the following is a specification.

This invention relates to automobile torpedoes of the kind in which means are provided for heating the compressed air serving as the motive fluid, prior to its delivery to the propelling engine.

In such torpedoes as heretofore proposed, 15 it has been necessary in order to prevent injury to the propelling engine and other working parts of the heating system, due to excessive heat, to have them placed in connection with circulating sea water, thus 20 rendering it impracticable to obtain the greatest possible thermal efficiency desired from the preheating, and the chief object of the present invention is to obviate this difficulty.

According to this invention, in order to 25 prevent any heat which may be radiated from the heating system from penetrating the balance chamber, and thereby detrimentally affecting the working of the hydrostatic valve contained therein, a hollow 30 partition is provided between the aforesaid watertight compartment and the balance chamber, this hollow partition being kept cool by the passage of sea water through it 35 during the travel of the torpedo through the water. For this purpose the said partition may be open at its lower and upper parts to the sea water. Instead of employing the 40 above mentioned water cooled partition, the hydrostatic valve, together with the other mechanism in the balance chamber may be 45 enclosed in a hollow casing through which cooling water is caused to pass.

In order that the said invention may be 50 clearly understood and readily carried into effect the same will be described more fully with reference to the accompanying drawings in which:—

Figure 1 is a diagrammatic longitudinal 55 section through a torpedo showing a form of the aforesaid hollow partition. Fig. 2 is a local view showing the said partition more clearly. Fig. 3 is a face elevation of the partition. Fig. 4 is a section taken on the line 1, 1 of Fig. 3, and Fig. 5 is a sectional

elevation showing diagrammatically the aforesaid hollow casing containing the hydrostatic valve.

A is the shell of the torpedo, A' is the balance chamber containing the hydrostatic 60 valve A', A² is the chamber containing the propelling engine A^{2x} and the air heating apparatus. This apparatus is similar to that set forth in my concurrent application Serial No. 794824 and comprises a helical air 65 tube E.

E^x is the compressed air container.

F represents the liquid flask and G represents the hollow partition between the 70 chambers A' and A².

The partition G that divides the chambers A' and A² is as shown by Figs. 2, 3 and 4 formed by two doors which are attached in a watertight manner to annular brackets or rings g on the inner surface of the torpedo shell, leaving a space between the doors for the circulation of the sea water. These brackets or rings are dished as shown for the 75 reception of a part of the helical tube E. The lower opening g' is directed toward the 80 forward end of the torpedo and the upper opening g² toward the rear of the torpedo. By these means the water is scooped up by the lower opening and forced through the partition and out of the upper opening thus 85 insuring a constant flow of sea water through the space.

Fig. 5 shows the arrangement in which the hydrostatic valve is surrounded by a hollow 90 casing A^{xx} through which sea water passes, this casing being provided at or near its lower end with a forwardly extending pipe a^x in communication with the sea and at or near its upper end with a rearwardly extending pipe a^{xx} also in communication with 95 the sea.

What I claim and desire to secure by Letters Patent of the United States is:—

1. In an automobile torpedo, the combination with the compressed air container, the propelling engine driven by the compressed air, the air heating apparatus, the chamber containing said apparatus, and the balance chamber, of a hollow partition between said chamber and means for causing water to circulate through said partition. 100

2. In an automobile torpedo, the combination with the compressed air container, the propelling engine driven by the compressed air, the air heating apparatus, the chamber 110

containing said apparatus, and the balance chamber, of a hollow partition between said chambers, said partition having openings at its top and bottom portions in communication with the sea water.

3. In an automobile torpedo, the combination with the compressed air container, the propelling engine driven by the compressed air, the air heating apparatus, the chamber containing said apparatus, and the balance chamber, of a hollow partition between said

chambers, said partition having an opening at its lower part directed toward the front of the torpedo and an opening at its upper part directed toward the rear of the torpedo. 15

In testimony whereof I affix my signature in presence of two witnesses.

FRANKLIN ELIJAH SMITH.
